UNITED STATES PATENT OFFICE.

JOHN A. PERRINGS, OF SPRINGFIELD, ILLINOIS.

CHINCH-BUG KILLER.

1,377,273.

Specification of Letters Patent. Patented May 10, 1921.

Application filed June 19, 1919. Serial No. 305,294.

To all whom it may concern:

Be it known that I, JOHN A. PERRINGS, a citizen of the United States, residing at Springfield, in the county of Sangamon and State of Illinois, have invented a new and useful Chinch-Bug Killer, of which the following is a specification.

The invention relates to appliances for killing chinch bugs or other insects which are destructive to crops. The general purpose of the invention is to provide means whereby a vaporizable substance, which is in its nature destructive to insect life, may be used to destroy insects without danger to the person using it; and to provide simple and effective means for controlling the application of the insecticide.

Other purposes of the invention are:

To provide a light and strong supporting structure; to provide a container for the destructive substance; to provide a removable closure for said container; to provide a heat-controlled instrument for operating said closure; to provide means for applying moderate heat to said instrument, and to provide other new and useful structural details.

The invention is illustrated in the annexed drawings, to which reference is hereby made, and will now be described and the novel features thereof will be recited in the claims.

Figure 1 is a front elevation of an apparatus embodying my invention; Fig. 2 is a rear elevation of part of the same apparatus; Fig. 3 is an oblique section on the line 3—3 of Fig. 1; Fig. 4 is a horizontal transverse section on the line 4—4 of Fig. 1; Fig. 5 is a perspective view of the closure latch; and Fig. 6 is a reduced perspective view of the detached frame of the apparatus. The same reference numerals designate the same parts in all the views.

The frame supporting the several parts of the apparatus is preferably of stiff wire, bent to form a vertical leg 1, horizontal feet 2, a shoulder 3, an eye 4, and an inclined leg 5.

The metal bed-plate has a transverse hole 8 accommodating the cylindrical container 9; and a transverse hole 10 accommodating the cylindrical generator 12. A set screw 13 secures the container in place in the bed-plate; and a set screw 14 secures the generator in place in the bed-plate. The container and the generator are detachable

from the bed-plate for convenience in filling them; and also to admit of compact storing of the parts for transportation.

The container 9 is a metal cylinder closed at one end and having at its open end an integral flared circular flange 15. The open end of the cylinder is finished flared so that the inner face of the closure 16 will have air-tight contact with the flared end of the cylinder.

The closure 16 is a circular metal plate having its circumference finished to seat in the flared end of the container, also having a central boss 17 having a transverse groove 18. When the closure 16 is in place in the flared end of the container 9, the latch 21 will be placed, from below, so that the boss 17 will occupy the transverse notch 22, and the springy members 23 will engage the flange 15 to cause the latch to bear firmly against the closure 16 and hold it on its seat, to prevent untimely movement of the closure, and to safeguard against accidental discharge of the contents of the container.

The generator comprises a metal tube 12 held in place in the hole 10 of the bed-plate by a set screw 14; a tubular extension 25 stationary in one end of the tube 12; a screw 26 screwing into the extension 25; a gasket 27 between the head of the screw and the outer end of the extension and forming in conjunction with the screw a gas tight closure at one end of the tube; and a stopper 28 preferably of cork or rubber, fitting tightly in the other end of the tube and forming a gas tight closure at that end of the tube. A hook 29 screws into the stopper 28 and when the parts are assembled, as shown in Figs. 1 and 3, the hook 29 bears firmly on rod 20, and the rod occupying the groove 18 in the boss 17 presses against the boss 17 to hold the closure 16 firmly in the flared end of the container 9. The tube 12 is preferably of thin metal which would likely be injured by cutting screw threads on the inside of the tube; the extension 25, of thicker metal, is therefore used and is brazed or soldered in the tube as a matter of convenience in manufacture.

The screw 26 may be removed for charging or cleaning the generator.

The generator is designed to contain a material which under the influence of mild heat, applied for a considerable time on the outer surface of the tube, will generate a gas having sufficient explosive energy to

violently expel the stopper 28. I prefer to use the material known as mustard gas, but any other suitable material having the properties stated may be used without departure from my invention.

The heater comprises a tube 30 of thin metal, having a hook 31 which hooks around the generator tube 12 to support the heater directly under the generator. A spring 33, 10 movable vertically within the tube 30, clasps a stick of punk 32, and admits of vertical adjustment of the punk within the heater to control the heat as may be required.

To prevent waste of the substance 15 charged from the container 9, I provide a pan 6 to contain the appliance and receive the discharged substance.

The substance used in the container being of a kind which might be deleterious to 20 the user of the appliance, I provide the latch 21 as a safeguard against untimely discharge of the contents of the container, and I provide means for very slow heating of the generator, so that the user may have ample 25 time to leave the place where the appliance is being used before the contents of the container can be released and become effective.

The substance used in the container and 30 the material used in the generator are prepared under special formulas; inasmuch however, as this application relates solely to mechanical appliances for utilizing said substance and said material it is deemed unnecessary to herein recite more clearly than 35 has already been done the nature and properties of said substance and said material.

The mode of operation of the appliance is as follows: The container 9, will be first 40 filled with the insecticide substance and closed and the closure 16 secured by the latch 21. The rod 20 will then be placed in the groove 18 of the boss 17 and the free end of the rod will be pressed against the end of 45 the stopper and upward under the hook 29 and the rod bearing against the hook and the boss will hold the closure firmly in the end of the container. Immediately before using, the screw 26 will be removed and the 50 generator will then be partly filled with the gas-generating material and the screw will be replaced and the latch 21 may then be safely removed by hand.

The apparatus will then be placed in the 55 pan 6 and the pan will be placed where the apparatus is to be used. The heater 30 will then be hung on the cylinder 12 and the punk lighted.

In due course of time, say about twenty minutes, the slowly burning punk will have 60 heated the generator to such extent that the material in the generator will have produced enough gas to blow out the stopper 29 and thereby cause the rod 20 to pull the closure 16 away from the container 9, to permit the 65 contents of the container to fall into the pan 6, to be vaporized there and gradually applied on and around the crop infested by the chinch bugs or other insects and thus 70 destroy the bugs or insects.

I do not restrict my claims to the precise details of construction herein set forth, since it is obvious that minor details may be varied without departure from my invention.

What I claim as new and desire to secure by Letters Patent is:

1. In an appliance of the class described, the combination of a container; a removable closure closing the container; a generator 80 adjacent to the container; a propulsive stopper closing one end of the generator; and a connecting device operatively connecting the propulsive stopper of the generator with the removable closure of the container.

2. In an appliance of the class described, the combination of a container; a closure closing the container; a generator adjacent to the container; a propulsive closure closing the generator; means operatively connecting 90 said closures, and means for applying mild heat to the generator to cause ejection of said propulsive closure.

3. In an appliance of the class described, the combination of a container having a circumferential flange; a closure seating in one end of the container and having a central boss; and a safety latch having a notch to accommodate the boss of the closure and having members engaging the circumferential 100 flange of the container.

4. In an appliance of the class described, the combination of a pan; a stand in the pan, a bed-plate supported by the stand; a container on the bed-plate; a closure closing 105 the container; and means for removing the closure to cause the contents of the container to fall into the pan.

In witness whereof I have hereunto signed my name at Springfield, Illinois, this 4th day of June, A. D. 1919.

JOHN A. PERRINGS.
